W. D. COLVIN & C. D. BARTHolemew.
AIR SUPPLY HEATER FOR CARBURETERS.
APPLICATION FILED MAR. 14, 1918.

1,281,139.

Patented Oct. 8, 1918.

UNITED STATES PATENT OFFICE.

WERT D. COLVIN AND CHARLES D. BARTHOLOMEW, OF BEARDSTOWN, ILLINOIS.

AIR-SUPPLY HEATER FOR CARBURETERS.

1,281,139.

Specification of Letters Patent.

Patented Oct. 8, 1918.

Application filed March 14, 1918. Serial No. 222,425.

To all whom it may concern:

Be it known that we, WERT D. COLVIN and CHARLES D. BARTHOLOMEW, citizens of the United States, residing at Beardstown, in the county of Cass and State of Illinois, have invented certain new and useful Improvements in Air-Supply Heaters for Carbureters, of which the following is a specification.

10 This invention relates to an improved air supply heater for carbureters and has as its primary object to provide a device of this character which may be readily connected to substantially any conventional type of carbureter now in common use for heating the main air supply as it is delivered to the carbureter and thus assist in vaporizing the liquid fuel and consequently increase the efficiency of the fuel mixture to accordingly 20 enhance the efficient operation of the engine with which the device is associated.

The invention has as a further object to provide a device of the above described character which will heat the supply of air 25 delivered to the carbureter to such degree that, by a corresponding increase in the easy vaporization of the liquid fuel, a material resultant saving in the quantity of liquid fuel consumed will be effected.

30 The invention has as a still further object in this connection, to provide a device making it easily possible to start an engine in cold weather.

A still further object of the invention is 35 to provide a device of the above described character employing an electric heating element which may be included in circuit with a storage battery or other suitable source of electrical energy upon the vehicle and wherein 40 in such circuit may be controlled by a manually operable switch so that when it is desired to render the device inactive, such result may be easily accomplished by operating the switch.

45 And a still further object of the invention is to provide a construction wherein the heating element will be protected from direct currents of air by a suitable baffle plate but wherein the said plate will be so formed 50 that air currents will be caused to eddy around the heating element so that all of the air passing through the device will be effectually heated.

Other and incidental objects will appear 55 as the description proceeds, and in the drawings wherein I have illustrated the pre-

ferred embodiment of the invention, and wherein similar reference characters designate corresponding parts throughout the several views:

Figure 1 is a fragmentary side elevation showing our improved air heater applied to a conventional type of carbureter, a portion of the carbureter being broken away to show the manner in which the improved device, 65 which is illustrated in section, is connected with the carbureter.

Fig. 2 is a vertical sectional view taken on the line 2—2 of Fig. 1, and looking in the direction of the arrows, this view clearly 70 illustrating the mounting of the heating element of the device.

Fig. 3 is a transverse sectional view taken on the line 3—3 of Fig. 2 and looking in the direction of the arrows, this view particularly bringing out the disposition of the baffle plate employed and its location with respect to the heating element, and

Fig. 4 is a perspective view showing the 80 baffle in detail.

In order that the construction, mounting and operation of our improved air supply heater may be accurately understood, we have, in the drawings, illustrated the device in connection with a conventional type of carbureter 10 having a main air inlet passage 11. At its upper end the body of the carbureter is adapted for attachment to an intake manifold of an internal combustion engine, as shown at 11'.

90 In carrying out the invention we employ a tubular casing or body 12 which is preferably formed of suitable sheet metal and is tapered from end to end. The smaller inner end of the body is, as particularly shown 95 in Fig. 1, adapted to frictionally engage within the outer end of the inlet passage 11 of the carbureter for thus detachably connecting the device with the carbureter. This provides an arrangement whereby the heater 100 may be readily mounted in position and in this connection it should be noted that the inner end of the casing is of such diameter that the said casing may in the manner indicated, be readily engaged with substantially 105 any conventional type of carbureter now in common use. Fitted through the casing adjacent its inner extremity are oppositely disposed radial terminals 13 and 14 respectively. These terminals are insulated 110 with respect to the casing by suitable split thimbles 15 of insulating material and at

their inner ends receive binding nuts 16. Fitted upon the terminals beneath these nuts are washers 17 which seat against the inner ends of the thimbles 15 and threaded upon the terminals to engage the outer ends of the said thimbles are nuts 18 coacting with the nuts 16 for detachably connecting the said terminals with the casing. At their outer ends the terminals 14 receive binding nuts 19. Extending between the inner ends of the terminals is a helically bent heating element 20. The ends of this heating element are interposed between the nuts 16 and washers 17 in which position they are clamped by proper adjustment of the said nuts for establishing electrical connection between the terminals and the heating element.

Associated with the heating element 20 is a baffle 21 therefor, shown in detail in Fig. 4 of the drawings. This baffle is preferably constructed of a single piece of suitable sheet metal and the body thereof is bent transversely to provide outwardly diverging wings 22. The baffle is of a length to extend diametrically of the casing 12 in front of the heating element and centering the baffle with respect to the said element as well as supporting the baffle in position, are laterally directed ears 23. These ears are preferably integrally formed on the ends of the baffle body and at their outer extremities are apertured to loosely receive the thimbles 15, as particularly shown in Fig. 1, and are thus secured to the casing by the terminals 13 and 14 extending through the said thimbles. By this arrangement, the thimbles also act to insulate the baffle with respect to the said terminals.

Leading from the storage battery or other suitable source of electrical energy upon the vehicle using our improved device, is a wire 24 connected to the terminal 13 and leading from the terminal 14 is a wire 25 which may be grounded. Current will thus flow through the heating element 20. However, it should be stated that a switch located conveniently to the driver's seat of the vehicle, is included in the circuit with the heating element so that the flow of current therethrough may be easily controlled. Such switch may be of any conventional type and has not been shown. However, it will be clear that by properly operating the switch, the element 20 may, at any time desired, be quickly heated by flow of current therethrough and, as will now be clear, currents of air drawn through the casing 12 into the main air inlet passage 11 of the carburetor, will be heated from the said heating element before being delivered to the carburetor. Vaporization of the liquid fuel within the carburetor will accordingly be accelerated with a consequently enhanced efficiency of the fuel mixture. In this way material resultant saving in the quantity of

liquid fuel consumed will not only be effected but, moreover, the efficient operation of the engine will be enhanced correspondingly. Furthermore, since a constant supply of heated air will be delivered to the carburetor the engine may be readily started in cold weather.

Attention is now directed to the fact that since the baffle 21 is arranged directly in front of the heating element, the diverging wings of the baffle will direct the currents of air flowing through the casing in opposite directions against the sides of the casing away from the heating element so that such inwardly flowing currents of air will be prevented from striking directly against the heating element to cause uneven contraction thereof and its premature breaking. However, it will be noted that the baffle is supported a considerable distance in front of the heating element, the outer edges of the wings of the baffle terminating in a plane only touching the adjacent sides of the coils of the said element. Consequently, the currents of air directed against the opposite sides of the casing by the baffle wings 22 will be permitted to eddy back within the baffle between the said wings and around the heating element. A constant circulation of air currents about the heating element will thus be maintained so that practically all of the air flowing through the casing will be uniformly heated prior to its delivery to the carburetor.

It will therefore be seen that we provide a particularly efficient construction for the purpose set forth and a device which, at the same time, is characterized by extreme simplicity to thus make the operation and maintenance of the device particularly economical.

Having thus described the invention, what is claimed as new is:

1. A device of the character described including a tubular casing, terminals carried thereby and insulated with respect to the casing, a heating element extending between the said terminals, and a baffle mounted in front of the said element and provided with ears engaged with the said terminals for supporting the said baffle in position, the said ears being insulated with respect to the said terminals.

2. A device of the character described including a tubular casing, a heating element mounted therein, and a baffle supported in spaced relation in front of the heating element and having a body provided with outwardly diverging wings extending laterally at opposite sides of the heating element and terminating in a plane substantially in front of the said element.

3. A device of the character described including a tubular casing, a heating element supported therein, and a baffle mounted

within the casing and having diverging walls forming an eddy pocket therebetween at one side of said element.

4. A device of the character described including a tubular casing, a heating element supported therein, and a baffle mounted within the casing at one side of said element and having spaced walls forming an eddy pocket therebetween open to the said element.

5. A device of the character described including a tubular casing, a heating element arranged therein, and a baffle mounted in front of said element and having outwardly

diverging walls extending laterally with respect to the said element.

6. A device of the character described including a tubular casing, terminals carried thereby and insulated with respect to the casing, a heating element supported by said terminals within the casing, and a baffle mounted in front of said element and secured by the said terminals, the baffle being insulated with respect to the terminals.

In testimony whereof we affix our signatures.
